UNITED STATES PATENT OFFICE.

ROLLA C. CARPENTER, OF ITHACA, NEW YORK, ASSIGNOR TO ATLAS PORTLAND CEMENT COMPANY, A CORPORATION OF PENNSYLVANIA.

PROCESS OF FEEDING FINE FUEL.

SPECIFICATION forming part of Letters Patent No. 691,336, dated January 14, 1902.

Application filed August 7, 1901. Serial No. 71,172. (No specimens.)

To all whom it may concern:

Be it known that I, ROLLA C. CARPENTER, a citizen of the United States, and a resident of Ithaca, in the county of Tompkins and State of New York, have invented a new and useful Process for Feeding Fine Fuel, of which this is a specification, taken in connection with the accompanying drawings, in which the same reference characters refer to similar parts in the several figures.

Such of my inventions as are disclosed, but not claimed, in this application are claimed in my divisional application, Serial No. 79,319, filed October 21, 1901.

My invention relates generally to the method of burning pulverized fuel, more particularly adapted to the roasting of cement material in rotary furnaces, in which a jet of air containing pulverized carbonaceous fuel and the heated gases resulting from the combustion of such fuel pass up through the furnace as an axial core and heat the walls of the furnace by radiation in the manner indicated in the patent to Hurry and Seaman, No. 645,031, of March 6, 1900. My invention relates specifically to an improved method by which an air-jet initially of larger diameter and of lower pressure than that indicated as the preferred form of jet in the said patent may be successfully employed to heat these rotary furnaces.

Figure 1 shows a side elevation of a rotary furnace to which the apparatus for carrying out my new process has been applied, parts being shown in section. Fig. 2 is an end view of part of this device, portions being omitted to more clearly indicate the construction. Fig. 3 is a partial sectional plan view taken substantially along the axis of the furnace. Figs. 4 and 5 are details of a modified form of one part of my apparatus.

A is a rotary cylindrical furnace composed of a shell A², of wrought-iron or other suitable material, lined with a refractory material A³, such as fire-brick, this furnace being of the well-known type of rotary furnace adapted for use in burning cement. The furnace is mounted to revolve on suitable rings A', secured to the shell of the furnace and resting in antifriction-rollers B'. The gear D' about the middle of the shell is engaged by suitable

driving apparatus C', which serves to slowly rotate the furnace in the direction indicated by the arrow. (See Fig. 1.) The furnace is slightly inclined, as is shown in the drawings, to insure the proper feed of the cement material through it, and the upper end of the furnace projects into a vertical chamber B, which has suitable connection with a stack C through an archway or opening C² in the chamber. The chamber is formed with two openings closed by doors or covers B² B³, serving to permit access to the chamber for cleaning and also for inspection of the interior of the furnace. The conduit C³ for the cement material, which may be protected by a water-jacket, if desired, extends through the chamber B and into the upper end of the rotary furnace, so that the material is delivered into the furnace and is fed gradually down it, forming a longitudinal accumulation of cement material along the bottom and one side of the furnace, as is indicated in the drawings. The lower end or mouth of the furnace communicates with the exit or combustion chamber D, formed of refractory material F and having suitable strengthening-plates, the plate F' being on the outside of the chamber directly opposite the mouth of the furnace. The material falls from the lower end of the furnace upon the chute H, from which it passes into the rotating cooling-cylinder H', substantially similar in construction to the rotary furnace and well known in this art. Secured to the strengthening-plate F' is the platform or supporting-shelf F⁴ for the burners E' E², which project through suitable openings F² F³ in the side of the combustion-chamber opposite the mouth of the furnace. Suitable plates F⁷ may be employed to fit closely about the burner-tubes and serve to close the openings through which these tubes project into the combustion-chamber, these plates moving with the burner-tubes as they are adjusted. Upon the supporting-shelf F⁴ are formed two frames F⁵ F⁶, each inclosing one of the burner-tubes, which at this point is preferably formed with a square extension E⁴ about the tube, which is engaged by four bolts F⁸, passing through the frame at right angles to each other to readily adjust the position of the front end of each of the burner-tubes. (See Fig. 2.)

Pulverized carbonaceous fuel formed by pulverizing to an impalpable powder anthracite or bituminous coal, or a mixture of the two, is fed from the hopper G⁴, where a supply of this material is always maintained, by the screw conveyer G³, which gradually feeds this material down into the passage G², communicating with the blast-pipe G'. A continuous blast of air, which is preferably of low pressure, is maintained through this blast-pipe G' by any suitable means, such as a centrifugal blower G, which gives a moderate air-pressure. The blast-pipe communicates with the bifurcated pipe E, and, as shown in the drawings, the two burner-tubes are secured to the branches of this pipe by means of a short section of some flexible material E³, which serves to connect each one of the burner-tubes to the pipe E in a flexible manner, forming practically a ball-and-socket joint at this point. Any other connecting means may be employed, and since it is only necessary to have a very slight freedom of movement of the burner-tubes the ordinary slip-joint between the light sheet-metal pipes of which the burners are constructed is usually sufficient to allow this movement.

In Figs. 4 and 5 I have indicated a modified form of burner with a device for diverting part of a jet of fine fuel toward the side of the furnace, if desired. The burner-tube E⁵ has adjustably attached to it by the setscrew K⁵ the sleeve K⁴, which may be adjusted longitudinally of the burner-tube or angularly with respect thereto. The compound diverting-plate K is rigidly secured to this sleeve by the two attaching-pieces K³. The diverting-plate K is formed with one face K' preferably extending substantially parallel with the axis of the burner-tube, and the other inclined face K², which is intended to divert part of the jet of air and fine fuel issuing from the burner-tube away from the main portion of the jet, so that this part of the jet may be inclined, if desired, toward the wall of the furnace to act in a way in connection therewith similar to the action of the inclined jet E².

The operation of this apparatus is as follows: The burner E' is intended to produce a flame extending substantially parallel to the axis of the rotating furnace, and the burner is therefore trained to produce this result. The burner-tube is substantially parallel to the axis, as is shown in Fig. 2, and this burner is located a little to one side of the axis of the furnace. It will be apparent to those skilled in the art that by this apparatus a continuous uniform jet of air and fine fuel issues from the burner E' and enters the combustion-chamber, where it meets an additional supply of heated air which has entered the combustion-chamber after having passed up through the cement-cooling cylinder and been heated therein. The jet after being properly ignited burns continuously in the hot furnace with a comparatively steady flame, heating

the walls of the furnace and the material fed through the furnace by radiation in a well-known manner. The second jet of fine fuel issues from the burner E² and burns within the furnace in a manner similar to the other jet. This jet is inclined, as shown in the drawings, toward the adjacent furnace-wall, so that the outer envelope of this jet impinges slightly upon the mass of clinker or cement material which is fed down along one side of the furnace, as indicated. This jet and the envelope of intensely-heated gases surrounding this jet heat the adjacent cement material and the walls of the furnace at a point comparatively near the lower end of furnace to a much greater extent than they heat the other parts of the furnace, since the jet at this point has assumed an eccentric position with relation to the walls of the furnace, because the flame at this point is much nearer to the side of the furnace. This maintains a hot zone near the lower end of the furnace under all normal conditions of operation and insures the correct distribution of heat at the various parts of the furnace to secure the proper burning of the cement material.

It will be noted that by the means I have disclosed the inclination of the jet E² may be varied, so that there is a greater or less local heating effect at the point desired by reason of the greater facility with which heat is supplied to the furnace-walls at this point, as the jet is directed nearer to these walls. It is desirable in the ordinary operation of this apparatus to vary the degree of inclination from time to time to secure the best results and also in some cases when an abnormal aggregation of cement material adheres to the furnace-lining at any point it is desirable to direct the coal-jet so that the heat therefrom will have a greater action upon the furnace-lining at this point to remove such accumulation of cement. I do not desire that there shall be such direct impingement of the inclined jet upon the furnace-walls as will burn out the walls of the furnace in the hot zone, since any very direct impingement of a coal-jet will quickly destroy the furnace-lining. Whatever slight impingement occurs should preferably take place upon that part of the furnace that is protected by the mass of clinker or cement material; but even here any substantial impingement of the particles carried upon the air-jet is in practice prevented by the strong draft up the furnace, which tends to restore the inclined jet toward the axis of the furnace.

While I have shown the inclined coal-jet as operating in connection with a jet which enters the furnace substantially parallel to the axis of the same and which impinges very little, if at all, upon its walls, I wish to be understood that a single coal-jet may be employed, inclined toward the furnace-wall. It will be understood in such case that the advantages which I have set forth from the

slightly-inclined jet in heating the furnace-walls to produce a hot zone at the lower part of the furnace and to insure the proper burning of the pulverized fuel and the proper distribution of heat at various parts of the furnace to burn cement in the correct manner is secured when only a single slightly-inclined jet is employed.

While I prefer to employ jets of air and fine fuel of uniform character and of low pressure, as I have disclosed, nevertheless, jets produced by a higher initial air-pressure and produced by different apparatus may be employed. In place of the jet which I have shown as issuing from the burner E' such a high-pressure compound jet as is shown in the Hurry and Seaman patent may be employed. Such a jet may also be used in place of the slightly-inclined jet E² either when the jet E² is used in connection with the jet E' or when it is used alone, as I have described. Other modifications may be made in the form, number, and arrangement of the jet or jets. Furthermore, any desired apparatus may be employed for producing jets of air and fine fuel and for introducing them into the furnace.

The inclination of the jets or of any desired portion thereof may be accomplished instead of inclining the burner-tube from which a jet issues by the diverting-plate which I have shown in Figs. 4 and 5, which serves to divert part of the jet, as has been explained, away from the body of the jet, so that this diverted part of the jet may be turned toward the walls of the furnace. Any other desired arrangement of diverting plate or plates may be employed, and these may be adjustably mounted upon the burner-tube to incline a greater or less portion of the jets toward the walls of the furnace. Such diverting-plates may be employed, if desired, to divert an entire jet. Numerous other modifications of my apparatus and method of using the same might be employed by those skilled in this art. I do not, therefore, wish to be limited to the disclosure which I have made in this case; but what I wish to secure by Letters Patent is set forth in the appended claims.

What is claimed as new is—

1. The process of feeding fine fuel into a rotary cement-furnace which consists in producing jets of air and fine fuel and in directing such jets into said furnace to assume an eccentric position in said furnace to produce a hot zone in said furnace by the eccentric position and by the proximity of such jets to the walls of said furnace.
2. The process of feeding fine fuel into a rotary cement-furnace which consists in producing jets of air and fine fuel and in directing such jets into said furnace to cause part of such jets to assume a position in proximity to the walls of said furnace to produce a hot zone in said furnace by the proximity of part of such jets to the walls of said furnace.

3. The process of feeding fine fuel into a rotary cement-furnace which consists in producing jets of air and fine fuel, in directing such jets into said furnace and in inclining part of such jets toward the walls of said furnace to produce a slight impingement thereupon.

4. The process of feeding fine fuel to a rotary cylindrical cement-furnace which consists in producing uniform jets of air and fine fuel and in directing such jets into the rotary furnace at an inclination to produce a hot zone in said furnace by the inclination of said jets toward the walls of said furnace.

5. The process of feeding fine fuel into a rotary cement-furnace which consists in producing jets of fine fuel, in feeding such jets into said furnace substantially parallel to the axis thereof and in simultaneously inclining part of such jets toward the material in said furnace to maintain a hot zone in said furnace.

6. The process of feeding fine fuel into a rotary cylindrical cement-furnace which consists in producing jets of air and fine fuel, in directing such jets into said furnace and in inclining part of such jets toward the walls of said furnace.

7. The process of feeding fine fuel into a cylindrical cement-furnace which consists in producing uniform low-pressure jets of air and fine fuel, in directing one of such jets into said furnace substantially parallel to the axis thereof and in inclining another of such jets toward the walls of said furnace.

8. The process of feeding fine fuel into a rotary cylindrical cement-furnace which consists in producing a jet of air and fine fuel and in directing such jet into said furnace to assume a position in proximity to the walls of said furnace to produce a hot zone in said furnace by the proximity of such jet to the walls of said furnace.

9. The process of feeding fine fuel into a cylindrical cement-furnace which consists in producing a jet of air and fine fuel and in directing such jet into said furnace to incline toward the walls of said furnace to produce a hot zone in said furnace by the proximity of such jet to the walls of said furnace.

10. The process of feeding fine fuel into a rotary cylindrical cement-furnace which consists in producing a jet of air and fine fuel and in directing such jet into said furnace toward the material in said furnace to slightly impinge upon the material treated in said furnace to maintain a hot zone in said furnace.

11. The process of feeding fine fuel into a rotary cement-furnace which consists in producing a jet of fine fuel and in directing such jet into said furnace toward the material in said furnace to slightly impinge upon the material treated in said furnace to maintain a hot zone in said furnace.

12. The process of feeding fine fuel into a cement-furnace which consists in producing a jet of fine fuel and in directing such jet into said furnace to assume a position in proximity to the walls of said furnace to produce a

hot zone in said furnace by the proximity of such jet to the walls of said furnace.

13. The process of feeding fine fuel into a rotary cement-furnace which consists in producing jets of fine fuel and in directing such jets into said furnace to assume a position in proximity to the walls of said furnace to produce a hot zone in said furnace by the proximity of such jets to the walls of said furnace.

14. The process of feeding fine fuel into a rotary cement-furnace which consists in producing jets of fine fuel and in directing such jets into said furnace to assume an eccentric position in said furnace to produce a hot zone in said furnace by the eccentric position of such jets in said furnace.

15. The process of feeding fine fuel into a rotary cement-furnace which consists in producing jets of air and fine fuel and in directing such jets into said furnace to assume an eccentric position in said furnace to produce

a hot zone in said furnace by the eccentric position of such jets in the hot zone of said furnace.

16. The process of feeding fine fuel into a rotary cement-furnace which consists in producing jets of fine fuel and in directing such jets into said furnace to cause the eccentric position of part of such jets near one end of the furnace to produce a hot zone in said furnace.

17. The process of feeding fine fuel into a rotary cement-furnace which consists in producing a jet of fine fuel, in feeding such jet into said furnace to cause such jet to assume an eccentric position with relation to the walls of the furnace to produce a hot zone in said furnace.
